FLUSH TANK CONSTRUCTION

Charles H. Topp, Huntington, W. Va.

Application April 22, 1939, Serial No. 269,513

1 Claim. (Cl. 4-43)

This invention relates to flush tank construction, and more particularly to the water control mechanism thereof, the primary object of the invention being to provide means for creating a siphonic action within the discharge pipe of the tank to discharge the water, thereby eliminating the usual ball valves commonly employed in controlling the water of flush tanks, and which frequently become defective, allowing the water to leak.

An important object of the invention is to provide means which will create an air-lock within the discharge pipe of the tank to normally prevent the flow of water from the tank, means being also provided for breaking the air-lock, allowing the water to flow, when it is desired to release the water.

Another object of the invention is the provision of a float which will move to its uppermost position when released, to break the air-lock and start the siphon, means being provided for limiting the upward movement of said float.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an elevational view illustrating a control mechanism, constructed in accordance with the invention.

Figure 2 is a plan view of the mechanism, the upper end of the float and float control bar, being shown in section.

Figure 3 is a sectional view taken on the line 3-3 of Figure 2.

Figure 4 is a sectional view taken on line 4-4 of Figure 2.

Referring to the drawings in detail, the reference character 5 designates a flush tank, which is of the usual and well known construction. It will of course be understood that the tank is supplied with the usual inlet pipe and valve controlling the passage of water into the tank, but since the inlet pipe and valve controlling the water passing therethrough plays no part in this invention, it has not been illustrated.

The reference character 6 designates the outlet pipe which establishes communication between the flush tank and the closet bowl with which the flush tank is used.

Mounted within the flush tank, is an outlet pipe 7 which has its discharge end extending into the outlet pipe 6. As shown by Figure 4 of the drawings, the outlet pipe 7 is provided with a passageway 8, adjacent to the discharge end thereof, and formed by an integral pipe section housing the discharge end of the outlet pipe. The overflow pipe indicated at 9 connects with the passageway 8, and directs overflow to the outlet pipe 6.

The outlet pipe 7 is curved and is provided with a downwardly extended end portion 10 terminating in an upwardly extended portion 11, the end of the portion 11 being open, so that water may pass into the outlet pipe.

Ribs 12 are formed at opposite sides of the upwardly extended portion 11 of the pipe 7, and provide guides, throughout the length of the upwardly extended end portion 11, for the float which is indicated by the reference character 13, and which moves over the upwardly extended portion 11 of the pipe 7.

The float 13 is hollow, the lower end thereof being open, so that it will fit over the upwardly extended end portion 11 of the pipe 7. The float is provided with a reduced end portion providing a shoulder 14 adapted to be engaged by the lower end of the bar 15 which forms a part of the operating lever 16 which is pivotally mounted on the bracket 17 forming a part of the structure.

The bar 15 is formed integral with one end of the operating lever 16, and is provided with longitudinal ribs 18 extending laterally from one edge thereof, the upper ends of the ribs extending along the upper edge of the bar 15, as at 19.

Secured to the float 13, are spaced arms 20 that have inwardly extended end portions 21 that engage the float 13 to insure the true vertical operation of the float at all times.

It might be further stated that the float is appreciably longer than the upwardly extended end portion 11 of the outlet pipe, so that a space is provided between the top of the float and open upper end of the upwardly extended portion 11.

The bar 22, which has connection with the operating knob, not shown, is connected with the operating lever 16, through the medium of the rod 23.

Thus it will be seen that due to the construction shown and described, the water flowing into the flush tank, will pass upwardly between the inner surface of the float and upwardly extended portion 11 of the pipe 7, compressing air in the space between the float and upper end of the upwardly extended portion 11.

When the lever 16 is moved upwardly, to the

position as shown in dotted lines in Figure 1 of the drawings, it is obvious that the float 13 will move upwardly to create a siphonic action within the pipe 7, causing the water in the flush tank to flow therefrom.

As the float moves upwardly, the arms 20 engage the inwardly extended portions 19 of the ribs 18, restricting further upward movement of the float.

As the water passes from the flush tank, it is obvious that the bar 15 will swing to a position as shown in full lines in Figure 1, and the float will be held in its normal position by the lower end of the bar 15 engaging the shoulder 14.

With the float in the position as shown by Figure 1, it is obvious that water passing into the tank will find its way into the space between the float and upwardly extended end portion 11 of the pipe 7, compressing air to provide an air-lock at the upper end of the pipe 11.

What is claimed is:

In a flush tank, an outlet pipe extending into the tank and having a downwardly and upwardly extended end portion, a hollow float positioned over the upwardly extended end of said pipe normally closing said pipe, said float being spaced from the pipe providing a water and air space, and adapted to create an air-lock at the end of the outlet pipe, a pivoted bar mounted within the tank and adapted to engage said float holding the float in its active position, ribs on said bar, arms on the float and engaging said ribs and adapted to guide said float in its vertical movements, means for operating said bar to release said float, and said float adapted to operate to cause a siphonic action within the pipe whereby the water in the tank is siphoned from the tank.
